UNITED STATES PATENT OFFICE.

SAMUEL M. RIKER, OF CHESTER, NEW JERSEY.

BELT BUCKLE.

Application filed August 15, 1922. Serial No. 581,996.

To all whom it may concern:

Be it known that I, SAMUEL M. RIKER, a citizen of the United States, residing at Chester, in the county of Morris and State 5 of New Jersey, have invented certain new and useful Improvements in Belt Buckles; and I do hereby declare the following to be a full, clear, and exact description of the invention, such as will enable others skilled 10 in the art to which it appertains to make and use the same, reference being had to the accompanying drawings, and to characters of reference marked thereon, which form a part of this specification.

15 This invention has reference, generally, to improvements in belt buckles; and the invention relates to a novel construction of plate buckle having a detachable gripping or clamping means slidably related to the 20 main body thereof, and to which one end of the belt is fixed; said gripping or clamping means being held in gripping relation to the adjustable end of the belt by the longitudinal strain or pull to which the latter is 25 subjected when in operative encircling relation to the waist of the wearer.

The invention has for its principal object to provide a very simple construction of plate belt buckle consisting of a main body 30 and a slideable gripping or clamping element separable from said main body, whereby the adjustable end of the belt may be once adjusted relative to the main body, and thereafter the belt may be taken on and off by 35 merely manipulating the separable gripping or clamping element to attach or detach the same from operative relation to said main body; said gripping or clamping element, when attached to the main body, being 40 adapted to automatically slide thereon into operative gripping or clamping relation to the adjustable end of the belt, to securely hold the latter against displacement while 45 around the person of the wearer.

45 Other objects of this invention, not at this time more particularly enumerated, will be clearly understood from the following detailed description of the same.

With the various objects of this invention 50 in view, the same consists, primarily, in the novel construction of belt buckle hereinafter set forth; and the invention consists, furthermore, in the novel arrangements and combinations of the several devices and parts, 55 as well as in the details of the construction of the same, all of which will be more fully

described in the following specification, and then finally embodied in the claims appended thereto.

The invention is clearly illustrated in the 60 accompanying drawings, in which:—

Figure 1 is a front face view of the novel buckle with the belt operatively connected therewith; Figure 2 is a front face view of the novel buckle as related to the belt, but 65 showing the gripping or clamping element detached or separated from the main body of the buckle, whereby the belt ends are separated to permit the attachment or detachment of the belt relative to the waist of the 70 wearer; Figure 3 is a longitudinal section taken on line 3—3 in Figure 1; Figure 4 is a transverse section, taken on line 4—4 in Figure 3; and Figure 5 is a perspective view 75 showing the buckle with the gripping or clamping element separated from the main body thereof.

Similar characters of reference are employed in all of the hereinabove described views, to indicate corresponding parts.

Referring now to said drawings, the novel belt buckle comprises a main body consisting of a face or front plate 6, having at its longitudinal edges side flanges 7. Provided in said face or front plate 6 adjacent to its rearward end is a transverse slot or belt passage 8, and adjacent to its forward end is another transverse slot or belt passage 9. Pressed out of the body of said face or front plate 6, at a point intermediate the slots or belt passages 8 and 9, is an inwardly projected post 10, having at its free inward end a T-head providing shoulders 11 at opposite sides of the post, which shoulders are spaced away from the inner surface of said face or front plate 6. Also pressed out of the body of said face or front plate 6, rearward of said post 10, is an inwardly projected stop lug 12.

The separable gripping or clamping element comprises a clamp-plate 13, the forward transverse edge of which is provided with a plurality of gripping serrations 14. The rearward end of said clamp-plate may be doubled inwardly and back upon itself as at 15 if desired, so as to be spaced inwardly from the main portion of the clamp-plate. The body of said clamp-plate 13 is provided with a suitably disposed opening 16, connected integrally with said clamp-plate 13 at the rearward edge of said opening 16, and so as to extend longitudinally

forward from the latter, are a pair of spring fingers 17 which are laterally separated or spaced so that at a proper time the post 10 of the main body of the buckle may pass between the same. Said spring fingers 17 terminate short of the forward edge of said opening 16 so as to provide a free transverse space of sufficient area to permit the T-head of the post to be inserted therethrough past the ends of said spring fingers. Said spring fingers 17 are each provided upon their inner faces, adjacent to their free ends, with stop-tits 18. Suitable means are provided in connection with the clamp-plate 13 for affixing or attaching thereto one end of a belt 19. Such means may be made in various ways. Illustrative of one form of such attaching means is a lever clamp device as shown in the drawings, which device consists of a pair of perforate bearing ears 20 turned inwardly from each side of said clamp-plate 13 adjacent to its forward transverse edge. Pivotally supported between said perforate bearing ears 20, is a clamp device 21 having at its respective ends trunnions or journals 22 which are engaged in the perforations of said bearing ears 20. The lower free edge of said clamp-device 21 is provided with a plurality of sharp gripping spurs 23, and extending rearwardly from the upper edge of said clamp-device 21 is a lever-arm 24. The end 25 of the belt 19, which is to be affixed to the separable gripping or clamping element, is inserted between the clamp-plate 13 and the clamp device 21 when the lever-arm 24 of the latter is raised to turn the gripping spurs 23 in a plane substantially parallel to the plane of the clamp-plate 13, whereupon the lever-arm 24 is turned down to thereby force the said gripping spurs 23 into biting and gripping relation to said belt end 25, as is most clearly illustrated in Figure 3 of the drawings. In order to hold the lever-arm 24 in downwardly folded position and against displacement, the free end of the same may be provided with downwardly curved catch-lips or lugs 26 which are adapted to snap over the rounded portion 27 of the doubled back end of said clamp-plate 13.

The free or adjustable end 28 of the belt 19 is inserted under the rearward transverse end of the face or front plate 6 to pass outwardly through the rearward slot or belt passage 8, then longitudinally across the outer face of front plate 6, and thence inwardly through the forward slot or belt passage 9 to issue forwardly from the opposite end of said front plate. If desired the rearward edge portion of said forward slot or belt passage 9 may be provided with a plurality of serrations 29 which tend to prevent accidental withdrawal of the belt from the main body of the buckle.

In applying the belt to the waist of the

wearer, the separable gripping or clamping element is separated from the main body of the buckle, and the belt 19 is arranged about the waist, whereupon the gripping or clamping element and the main body of the buckle are again brought together so that the T-head of the post 10 connected with the front or face plate 6 may be caused to enter through the opening 16 of the clamp-plate 13 at a point forward of the ends of the spring fingers 17. A forward longitudinal pull upon the clamp-plate 13 will thereupon slide the same forward relative to the main buckle body to cause its gripping serrations 14 to move into gripping engagement with the free end portion of the belt 19, to clamp the latter between said serrations 14 and the forward edge of said forward slot or belt passage 9 of the main buckle body. The forward sliding movement of said clamp-plate will also cause the spring fingers 17 to move forward on opposite sides of the post 10, which in turn causes the stop-tits 18 to spring or snap past the shoulders 11 of the T-head of the post 10, so as to locate the former at the forward side of the latter, in which position they serve to prevent accidental retraction of the clamp-plate 13 from operative belt end engaging position. The belt may be adjusted, if necessary, by moving the free end thereof forwardly relative to the main buckle body until the desired tension around the waist is established, under such manipulation the clamp-plate 13 being retracted sufficiently to release the serrations 14 thereof from operative gripping relation to the belt end. The desired tension, thus established, will always operate to pull the clamp-plate 13 forward so that the bite of the serrations 14 is maintained while the belt is worn. After an initial adjustment of the belt to the waist of the wearer, it is unnecessary to disturb the adjusted relation established between the free end portion of the belt and the main buckle body, since to remove the belt from the wearer's waist all that is necessary to be done is to push back the clamp-plate 13, until its rearward end is stopped by the stop-plug 12 of the main buckle body, whereby the clamp-plate is positioned so that the spring-fingers 17 and their stop-tits 18 have been retracted from beneath the shoulders 11 of the T-head of the post 10, and said T-head is alined with the open space 16, so that the main buckle body and clamp-plate 13 may be separated to part the respective ends of the belt. To replace the belt on the wearer's waist the operations thus effected are reversed.

From the above description it will be plain that the novel buckle structure above described is of exceedingly simple construction, comprised of few parts, and subject to a quick and easy manipulation for the pur-

pose of taking on and off the belt connected therewith from the waist of the wearer.

I am aware that some changes may be made in the various arrangements and combinations of the devices and parts, as well as in the details of the construction of the same, without departing from the scope of this invention as set forth in the foregoing specification, and as defined in the appended 10 claims. Hence, I do not limit my invention to the exact arrangements and combinations of the various devices and parts as described in said specification, nor do I confine myself to the exact details of the construction of 15 parts as illustrated in the accompanying drawings.

I claim:—

1. A belt buckle comprising a face plate, transversely slotted adjacent to its respective 20 ends for threading the free end of a belt adjustably therethrough, a post projecting inwardly from the inner face of said face plate intermediate said slots, a clamp plate detachably engageable with said post and 25 longitudinally slidable relative to said face plate and its post, mutually cooperative means on said post and said clamp plate for retaining the latter in operative attached 30 relation to said face-plate, and means for attaching the fixed end of a belt to said clamp plate.

2. A belt buckle comprising a face plate transversely slotted adjacent to its respective 35 ends for threading the free end of a belt adjustably therethrough, a T-head post projecting inwardly from the inner face of said face plate intermediate said slots, a clamp plate detachably engageable with said post, and longitudinally slidable relative to said 40 face plate and its post, said clamp plate having means cooperating with the lateral projections of said T-head post for retaining the clamp plate in operative attached relation to said face-plate, and means for attaching 45 the fixed end of a belt to said clamp plate.

3. A belt buckle comprising a face plate transversely slotted adjacent to its respective 50 ends for threading the free end of a belt adjustably therethrough, a T-head post projecting inwardly from the inner face of said face plate intermediate said slots, a clamp

plate having an opening therein to receive said T-head post for the separable engagement thereof with said face plate, said opening being restricted at its rearward end to 55 straddle the shank of said post, said clamp plate being longitudinally slidable relative to said face plate and its post, and means for attaching the fixed end of a belt to said clamp-plate.

4. A belt buckle comprising a face plate transversely slotted adjacent to its respective ends for threading the free end of a belt adjustably therethrough, a T-head post projecting inwardly from the inner face of 60 said face plate intermediate said slots, a clamp plate having an opening therein to receive said T-head post for the separable engagement thereof with said face plate, said clamp plate being longitudinally slidable relative to said face plate and its post, laterally spaced spring fingers projecting 65 forwardly into said opening from the rearward margin thereof, said spring fingers having stop-tits adapted to snap beneath 70 and past the lateral projections of said T-head when said clamp plate is slid operatively forward, and means for attaching the fixed end of a belt to said clamp plate.

5. A belt buckle comprising a face plate transversely slotted adjacent to its respective 75 ends for threading the free end of a belt adjustably therethrough, a clamp plate separable from said face-plate, mutually cooperative means on said face plate and said clamp plate for slidably relating the latter to the former, said clamp-plate having a plurality of gripping serrations at its forward edge, a stop-post connected with said face plate for determining the rearward 80 limit of movement of said clamp plate relative to said face plate, and means for attaching the fixed end of a belt to said clamp plate.

In testimony that I claim the invention 85 set forth above I have hereunto set my hand this 12th day of August, 1922.

SAMUEL M. RIKER.
